UNITED STATES PATENT OFFICE

ANDREW R. RIDDERSTROM, OF NAHANT, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY

FOLDING MACHINE

Original application filed June 24, 1921, Serial No. 480,177. Divided and this application filed April 19, 1923. Serial No. 633,120.

The present invention relates to folding machines, and more particularly to machines for folding a binding strip around the edge of a boot or shoe upper to which it is attached.

5 This application is a division of a copending application, Serial No. 480,177, filed June 24, 1921.

The binding strip is usually sewed upon a face of the upper along an edge thereof, 10 after which the strip is folded around the said edge and into even contact with the opposite face. In order that the binding strip, after folding, may lie evenly and smoothly against the said opposite face, it is necessary 15 that the strip be first wiped tightly across the edge to which it is secured and then pulled and held tightly during the folding operation and while it is pressed against the said opposite face; and it is necessary also 20 that the strip be folded exactly at the proper points or lines, and not to one side thereof.

An object of the present invention is to provide an improved machine adapted to fold binding strips of the above-described character.

With the above and other objects in view, the invention consists of the improved machine hereinafter described, illustrated in the accompanying drawings, and defined in the 30 appended claims.

In the drawings, Fig. 1 is a plan view of the forward part of the machine, upon a reduced scale; Fig. 2 is a fragmentary plan view, upon a larger scale than in Fig. 1, illustrating the operation of the preferred machine; Fig. 3 is a side elevation corresponding to Fig. 2; Fig. 4 is a detail view illustrating the action of the preferred wiper of the present invention; Figs. 5, 6 and 7 35 illustrate successive steps in the operation of this wiper; Fig. 8 is a section of a shoe upper, showing an unfolded binding strip attached thereto; and Fig. 9 is a section similar to Fig. 8, showing a binding strip in finally folded position upon the upper.

The invention is illustrated in the accompanying drawings in connection with the folding of a binding strip 2, of cloth, silk and the like, around the edge 4 of a sheet of leather or other material 6, such as a boot or

shoe upper. An edge 8 of the binding strip is stitched at 12 to a face 10 of the shoe upper along the edge 4, so that the sheet and the strip extend at an angle to each other from the secured-together edges 4 and 8. It will be understood that the invention is equally applicable to other articles than that which is herein chosen for purposes of illustration, and the elements of the article need not necessarily be of the relative dimensions shown.

The shoe upper is initially placed upon a platform or support 24, with the face 10 of the upper in contact with the support. An end of the free or unsecured edge 26 of the strip 2 is initially moved across and around the secured-together edges 4 and 8, and into the space between an interior side face 28 of a feed point 30 and a plow 32 that stands up integrally from a plate 34. The machine being set into operation, successive portions of the unsecured edge or portion of the strip 2 near the stitches 12 are intermittently wiped tightly across the secured-together edges 4 and 8, or away from the stitches, as shown more particularly at 36, Fig. 9, by the combined action of a wiper 602 and a retainer 153 that presses down heavily at this time upon the upper directly opposite to the point of action of the wiper. The wiper thus cooperates with the retainer at this time, to 50 wipe or stretch the strip tightly across the edge of the stock. The retainer-operating mechanism will not be described herein, as it forms no essential part of the present invention. The retainer is provided with teeth, the more firmly to hold the stock. In order to enable the wiper 602 to operate, the strip 2 is progressively moved lightly or loosely by the operator's fingers from the position of Fig. 8 more or less into the plane 55 of the shoe-upper sheet 6, as the shoe upper is fed forward through the machine. The successively wiped portions are initially intermittently folded around the secured-together edges 4 and 8 by the plow 32 and they 60 are gripped intermittently between the interior side face 28 of the feed point and the plow 32, becoming thereby pulled tightly. The intermittent wiping, and folding and 65 gripping operations are performed upon the 70

successive portions of the strip alternately during successive pauses in the feed, each wiped portion being folded by the plow. The folded portions are advanced by the feed point and a cooperating feed block 41, that is carried integrally with the plow 32 upon the plate 34, to a combined folder and fold presser 42. The fold presser folds the plow-folded portions of the strip further and 10 presses them down against the other face 16 of the sheet, as shown in Fig. 9. The preferred fold presser 42 is described in Letters Patent Nos. 1,527,395 and 1,527,396, granted February 24, 1925. These operations are 15 continued in timed relation to one another until the whole strip has become folded, as described in the said Letters Patent No. 1,527,396. Reference is made to the said Letters Patent for a fuller description of so much 20 of the machine as is not fully described herein, because unnecessary to an understanding of the present invention.

The specific wiper illustrated in the drawings and described herein acts intermittently, 25 at spaced or separated portions only of the strip, in a plane at right angles to the direction of feed, and from a point beneath the plane of the leather sheet to a point above the sheet. In Figs. 3 and 7, the wiper is shown 30 before it engages the strip. It then engages the strip, and moves as illustrated in Figs. 4, 5 and 6. This action of the wiper from a point beneath the plane of the sheet to a point above the sheet is considered to be a very important feature of the present invention, as 35 it insures tight wiping.

The wiper 602 is pivoted at 604 to a link 606 one end 608 of which is pivoted to a gear 610. The gear 610 is shown meshing with a 40 gear 64 upon a driving shaft 66. A stationary pin 612 in a slot 614 at the other end of the link 606 guides the back-and-forth movement of the link during the rotation of the gear 610. This back-and-forth movement of the 45 link is communicated, through the pivotal point 604, to the wiper 602. A stationary pin 616, in a slot 618 of the wiper, guides the diagonal movement of the wiper.

The initial position of the parts may be 50 regarded as shown in Fig. 4. As the gear 610 is rotated in the direction of the arrow, Fig. 4, the link 606 is drawn inward and upward slidingly and pivotally about the pin 612, towards the position indicated in Fig. 5. The wiper 602 is thus also carried inward and upward, and it is at the same time caused to 55 move diagonally by the action of the pin 616 upon the walls of the slot 618. Further rotation of the gear 610 will effect a downward, but a further inward, movement of the link 606, towards the position indicated in Fig. 6, which will have the effect of still further diagonally inclining the wiper 602. The net result of the movement of the wiper 602 thus far described is to force the wiper

tightly against the binding strip and diagonally upward, in the direction of the arrow, Fig. 5. As the gear 610 is further rotated, the link 606, and the wiper 602 to which it is pivoted, are moved away from the binding strip, the wiper moving downward and outward, in the direction of the arrow, Fig. 7. A diagonally acting wiper having a four-way motion and having a considerable range of movement oblique to the plane of the sheet 75 is thus provided.

The feeding mechanism 41, 30, and the combined folder and fold presser 42, are also driven from the driving shaft 66, as described in the said Letters Patent No. 80 1,527,396.

It will be understood that the invention is not restricted to the exact embodiment thereof that is herein illustrated and described, but that modifications may be made therein by persons skilled in the art, and that such modifications are considered to be embraced within the spirit and scope of the present invention, as defined in the appended claims.

What is claimed is:

1. A machine for wiping a strip across the edge of a sheet of material to one face of which, along the said edge, an edge of the strip is secured so that the sheet and the strip extend from the secured-together edges at an angle to each other, the said machine having, in combination, means for feeding the sheet, a wiper for wiping the strip across the secured-together edges, and means for actuating the wiper in a plane at an angle to the direction of feed in a direction oblique to the plane of the sheet.

2. A machine for wiping a strip across the edge of a sheet of material to one face of which, along the said edge, an edge of the strip is secured so that the sheet and the strip extend from the secured-together edges at an angle to each other, the said machine having, in combination, a member adapted to engage the strip at a point where the strip is secured to the sheet, and means for actuating the member in a plane at an angle to the direction of feed in a direction oblique to the plane of the sheet.

3. A machine for folding a strip around the edge of a sheet of material to one face of which, along the said edge, an edge of the strip is secured so that the sheet and the strip extend from the secured-together edges at an angle to each other, the said machine having, in combination, means for feeding the sheet, a wiper for wiping the strip across the secured-together edges, means for actuating the wiper in a plane at an angle to the direction of feed in a direction oblique to the plane of the sheet, and a fold presser for pressing the strip against the other face of the sheet.

4. A machine for wiping a strip across

the edge of a sheet of material to one face of which, along the said edge, an edge of the strip is secured so that the sheet and the strip extend from the secured-together edges at an angle to each other, the said machine having, in combination, a wiper for wiping the strip across the secured-together edges and provided with a slot, a pin in the slot for guiding the wiper, and means for imparting a four-way motion to the wiper.

5. A machine for wiping a strip across the edge of a sheet of material to one face of which, along the said edge, an edge of the strip is secured so that the sheet and the strip extend from the secured-together edges at an angle to each other, the said machine having, in combination, a wiper for wiping the strip across the secured-together edges, a link, one end of which is pivoted 15 to the wiper, a gear to which the other end of the link is pivoted, and means for driving the gear.

6. A machine for operating upon a piece of work which consists of a piece of material to which a piece of binding is attached 20 having, in combination, a support over which the work is fed intermittently with the side to which the binding is attached resting upon the support, a binding engaging member, 25 and means for moving said member from a point beneath the work to a point above the work to pull the free portion of the binding out over the attached portion.

7. A machine for operating upon a piece 30 of work which consists of a piece of material to which a piece of binding is attached, having, in combination, a support for the work, means for feeding the work, a member for engaging that part of the binding which is 35 in superposed relation to the material, means for moving the member from a point beneath the work into contact with the binding and to a point above the work to pull the free portion of the binding out over the attached 40 portion, and means for folding the pulled-out binding over upon the body of the work.

8. A machine for operating upon a piece 45 of work which consists of a piece of material to which a piece of binding is attached having, in combination, a support for the work, means for feeding the work intermittently 50 over the support, a wiper, means for causing the wiper to move intermittently from a point beneath the work to a point above 55 the work during the pauses in the intermittent feed to force the free portion of the binding over the attached portion, and means for folding the pulled-out binding about the edge of the material to form a fold and pressing it against the body of the work.

In testimony whereof, I have hereunto subscribed my name this 17th day of April, 1923.
